3,176,399 TOOL PUNCH WITH SPRING ACTUATED IMPACT MEANS

Anthony J. Marino and Anthony M. Belfiore, both of
559 Encinitas Ave., San Diego, Calif., and Adolph F.
Graf von Soden, 3909 Riviera Drive, San Diego, Calif.

Filed Sept. 20, 1962, Ser. No. 224,976
2 Claims. (Cl. 30—367)

This invention relates to hand tools and more particularly to impact apparatus and devices adapted for uses in making center mark impressions, chiseling, chipping, vibration producing oscillation for removing screws, nuts, bolts or studs, also for driving nails, finish nails in cabinet work and dowel pins, removing pins and keys, leather stenciling, riveting and heading of pins, rivets or the like, the use of said hand tool being accomplished without the use of a conventional hammer.

Accordingly an object of the invention is to provide a hand tool that may be made an integral part of a stapler, or be made a detachable part thereof, so that said hand tool may be used in inaccessible places or such positions where the use of a conventional hammer and a tool is impossible.

A further object of the invention is to provide said hand tool with a base having a center punch and a hingedly detachable and interchangeable scale rule, so that a measurement such as a radius may be easily taken and scribed and also a center punch may be easily employed and applied.

Another object of the invention is to provide said hand tool with a suitable tool bit frame which may be detachable or be made an integral part thereof, said tool bit frame having means for supporting a removable cutting tool or bit in position when said hand tool is in use.

A further object of the invention is to provide a suitable tool bit with a detachable chuck means adapted for regulating and for controlling the cutting position of said tool bit when same is in use and actuated by the reciprocating mechanism provided in said hand tool.

Another object of the invention is to provide said hand tool with means which may be reciprocal or a gear driven cam and operable by a suitable electrical motor, hydraulic or pneumatic unit or the like, adapted for securing oscillating motion for the tool bit attached thereto when in use.

The invention also has for its objects to provide such means that are positive in operation, convenient in use, easily installed in a working position and easily disconnected therefrom, economical in manufacture, relatively simple, and of general superiority and serviceability.

Other and further objects and advantages of the invention as will hereinafter more fully appear, are attained by the construction herein shown on the drawings and described in the specification, forming a part of the application.

Reference is had to the accompanying drawings, in which the similar reference characters denote the same parts.

In the drawings;

FIG. 1 shows a partly fragmentary side elevational and partly sectional view of the hand tool, taken on lines 1—1 of the FIG. 2.

FIG. 2 shows a front end view of the hand tool, taken from the right side of FIG. 1.

FIG. 3 shows a top view of the hand tool, showing the fragmentary section of a removable scale or a measuring rule in position, taken from the top of FIG. 1.

FIG. 4 shows a slightly enlarged and fragmentary sectional view of the tool bit frame, taken on lines 4—4 of FIG. 1.

2

FIG. 5 shows another and a slightly enlarged and fragmentary sectional view of the hand tool and the hammer apparatus therein, taken on lines 5—5 of the FIG. 3.

FIG. 6 shows the elevational view of the chisel tool bit structure.

FIG. 7 shows the elevational view of the marking tool bit.

FIG. 8 shows a vertically sectional view of the chuck having a chisel or cutting tool bit in position and having 10 a detachable handle associated therewith for regulating 15 the cutting position thereof when attached to said hand tool and in use.

FIG. 9 shows a side elevational view of the hand tool attached to a power unit.

FIG. 10 shows the top view of the hand tool connected 15 to a power unit, taken from the top of FIG. 9.

FIG. 11 shows a sectional plan of the chuck member, showing same in relative position to the extension handle when attached, taken on line 11—11 of FIG. 8.

20 Describing the invention more in detail, in its broader aspects, said invention comprises an attachment for a conventional impact hammer generally designated by numeral 2, having a base 4 provided with a pivoting handle 6 including a gripping bar 8.

25 Said impact hammer 2 which is a spring actuating type, is provided with a front enclosure or housing 10 consisting of a frame 12 for enclosing a movable bracket 14 also having an internally extending ledge 16 adapted for supporting and for retaining thereon an outer spring 18 and 30 an internally mounted adjustable power spring 20, both of said springs having a common top enclosure 22 provided with a threaded block or nut 24 and a suitable adjusting screw 26.

Said movable bracket 14 is slidably mounted within 35 the outer end of said housing 10 and is also provided with an end cover 28 for supporting said movable bracket 14 and for holding said nut 24 in position, while the lower end section 30 of said end cover 28 is provided with a downwardly extending tubular guide 32 which terminates with a threaded end 34 having a transverse slot 36 disposed at the extreme end thereof, as shown in FIG. 2.

A hammer plate 38 is secured to said movable bracket 14 which is slidably positioned between said end cover 28 and said outer end of said housing 10, so that a vertical 45 movement for said hammer plate 38 may be had; also, said hammer plate is provided with a downwardly extending end plate to which a hammer 40 is secured and adapted to slide within said tubular guide 32, as shown in FIGS. 1 and 5.

50 Said movable bracket 14 is also provided with a pair of inwardly extending pawls 42 adapted for engaging a tiltably actuating pawl 44 which is secured in a pivot section of said frame 2 and is pivoted upon a cross pin 46 and also upon which said pivoting handle 6 is pivotally mounted, said cross pin having the loop of a spring 48 mounted thereon and wherein one extended end of said spring is arranged to rest within said gripping bar 8 and the other spring end 50 extends to and rests at the inner side of said pivoting handle 6 which is adapted for urging said handle into an outwardly extended position and at the same time actuating said pawl 44 into a downwardly tilted position, as shown in FIG. 1.

The end of said tubular guide 32 is provided with a 65 removable locking sleeve 52 having an aperture 54 at its lowermost end and having the diameter of said aperture identical to the inside diameter of said tubular guide 32, which are adapted for slidably retaining therein the shank upper end of a center punch 56.

The upper end of said tubular guide 32 is provided with a pair of cross apertures or holes 58 which are disposed below the end of said downwardly extending hammer 40.

and which are arranged for receiving therein a pair of the locking ends 60 of a U-shaped lock spring 62, see FIG. 4, and of which the frontwardly extending end 64 is bent upwardly, as shown in FIG. 1, for securing an easy removal thereof from its mounted position when required.

Said cross apertures or holes 58 in their respective positions are arranged to pass partly into the interior of said tubular guide 32, as shown in FIG. 4, so that when said pair of locking ends 60 are in position then the inner surface edges thereof will engage an annular groove 66 disposed at the shank upper end 68 of said center punch 56, and thereby holding same in position when in use.

It may be noted that said annular groove 66 is wide in its structure for allowing a sliding motion for the shank end of said center punch 56 when held in position by means of said retaining spring locking ends 60.

In operation, when said hammer plate 38 is tripped by the downward action of said pivoting handle 6, which in its pivoting motion causes said springs 18 and 20 to become compressed and then causing said supporting internal ledge 16 to become released, it will carry downwardly said movable bracket 14 together with said hammer plate 38, and in its downward motion causing said internal ledge 16 to stop against a cross buffer 70, which consists of a pair of cross plates secured in said frame 12 and having a rubber layer 72 positioned therebetween, as shown.

When pivoting said handle 6 then said hammer 40 is raised accordingly and released and forced downwardly against the shank upper end 68 of said center punch 56, and, when it is desired to increase the force of impact against said bracket 14, then said adjusting screw 26 is forced downwardly against the adjustable inner power spring 20, so that a greater penetration of the point end 76 of said center punch 56 may be had.

For securing suitable measurements of a distance when using the center punch 56 and when measuring or marking a radius, angles or the like, the lower edge of said base 4 is provided with a pair of tubular eyelets 78 and 80 that are disposed at each side thereof, respectively see FIG. 2, to which a tiltable and removable bracket plate 82 is attached, which is interchangeable and adapted for mounting same in position at either side of said base 4 and arranged to be held in place by means of suitable locating pins 84, and which are secured in place by means of a suitable flexible member such as chain or the like, for preventing same from becoming lost or damaged.

Said tiltable and removable bracket plate 82 is pivotally and removably mounted as shown, and the tubular eyelets at each side of said base 4 provide means for using said removable bracket plate 82 at the side desired and most convenient for the user, that may be right handed or left handed, also, said removable bracket plate 82 is provided with an angularly extending retainer 86 having a longitudinal slot 88 wherein a suitable scale or measuring rule 90 is slidably and adjustably positioned and held in place by means of a fastening screw 92 for holding said scale or measuring rule in any desired longitudinally extended position.

When in use, said scale or measuring rule 90 may be used for measuring lengths and distances between points, a radius of a circle may be scribed and punched upon steel surfaces or plates and without the uses of a conventional hammer, and also, allowing said impact hammer 2 device to be used in close quarters or crowded places for making center punch marks or the like.

When said tubular guide 32 of said device is provided with a pin punch 96 as shown in FIG. 7, and held in place in the manner herein before provided, said pin punch 96 may be used in cabinet work for driving small and finish nails into position, and for performing other operations that may be found adaptable in practice.

Also, said tubular guide 32 may be provided with a

cutting tool such as a chisel 98, as shown in FIG. 6, wherein the shank thereof is provided with a pair of upset keys 100 which are adapted for engaging said transverse slots 36 disposed in said tubular guide 32, and when in position, the outwardly extending end 64 is then held in place by means of said U-shaped lock spring 62, so that the blade of said chisel may be used in wood for cutting openings, or be used for other cutting and engraving operations such as leather made items or the like.

Said chisel tool 98 may also be used in connection with a chuck 102 which is provided with a suitable shank extension or rod 104 and adapted for engaging said tubular guide 32 in a manner as herein before provided, also, said chuck 102 may, if so desired, be provided with a pair of sidewardly positioned apertures 106 and which are adapted for engaging the end prongs 107 of an extension handle 108, so that the position of the cutting blade of said chisel tool 98 may be controlled and directed or required when in use.

As shown in FIGS. 9 and 10, said housing 2 of said impact hammer is mounted and held in position between a pair of brackets or plates 112 and 114, respectively, having said tubular guide 32 extended longitudinally as shown, and in structure and assembly said impact hammer is arranged to have said tiltable pawls 44 of the mechanism to be connected to an extension rod or bar 116 which is adapted for connecting a conventional motion converter that is also speed reducing and oscillating unit 118, and which in operation is actuated by a suitable conventional power motor 120 that is supported and held in place and position by means of said brackets 112 and 114, as shown.

It may be noted that said motor 120 may be a suitable electrically operable unit, or said motor may be pneumatic or hydraulic type, so that in use said impact hammer device 2 may be operated in a conventional manner and using said interchangeable tools as in practice may be most desirable.

While this invention is described herein with great particularity, it will be clear that the same may be modified throughout a wide range.

Accordingly, it is not proposed that this invention be limited to the exact details of construction herein shown on the drawings and described in the specification, and therefore, reservations of the rights in practice are made, to the end that necessary changes and modifications may be had, which may come within the scope of the appended claims.

We claim as our invention:

1. In a hand tool impact device of the class described having a frame, a base in said frame, a front enclosure secured in said frame and a pivotally movable handle connected to said frame; a movable bracket slidably mounted in said front enclosure, a hammer plate mounted on said movable bracket extending downwardly therefrom and terminating in a hammer, an internal ledge at the bottom end of said movable bracket extending internally into said frame, a top enclosure disposed at the top of said front enclosure extending into and blending with said frame; a threaded nut supported by said top enclosure and lying in close proximity to the top of said front enclosure; an outer impact spring mounted between and carried by said internal ledge of said movable bracket and disposed against the inner side of said top enclosure, an inner power spring positioned within said outer impact spring, an adjusting screw adjustably engaging said threaded nut and engaging said inner power spring for adjusting an impact force to said movable bracket including said anvil associated therewith, said movable bracket and said pivotally movable handle having a set of pawl means for providing a tripping action for said movable bracket when actuating said movable and pivotally mounted handle, the combination of, a tubular guide extending downwardly from said front enclosure, said tubular guide having a threaded end section and a plurality of transversely cut slots at the end thereof, a locking sleeve secured on

said threaded end of said tubular guide, a pair of apertures passing through said front enclosure and said tubular guide, a center punch tool removably and interchangeably disposed in said tubular guide and supported by said locking sleeve when in position, a shank upper end in said center punch tool disposed in close proximity to and against the end of said hammer, an annular groove in said shank upper end, said annular groove disposed in close proximity to said pair of apertures in said front enclosure and said tubular guide, and a U-shaped lock spring secured in said pair of apertures for engaging said annular groove of said shank upper end and thereby holding said center punch tool in position and also for retaining same in place within said tubular guide when imparting a driving force and an impact against said shank upper end by said hammer and when said set of pawl means are tripped by the action of said pivotally movable handle of said hand tool impact device.

2. In a hand tool impact hammer device of the class described comprising, a frame having a base including 20 a front enclosure, a top enclosure in said front enclosure, a pivot section in said frame having a pivotally movable handle mounted therein and held in pivotal position by a cross pin mounted in said frame, a movable bracket slidably mounted in said front enclosure of said frame and also having a hammer connected to and downwardly extending therefrom, said movable bracket further including a pair of inwardly extending pawls and an inwardly extending ledge, a set of impact springs supported between said inwardly extending ledge and said top en- 30

closure, tripping pawls mounted on said cross pin and tiltably associated with said pivotally movable handle at said pivotal section of said frame for engaging said inwardly extending pawls and for tripping said movable bracket and thereby carrying with a driving force said movable bracket and said hammer, the combination of, a tubular guide having a threaded end extending downwardly from said front enclosure of said frame for guiding said hammer therein, a removable center punch slidably mounted in said tubular guide having an annular groove at the shank upper end thereof and disposed below said hammer, a locking sleeve engaging said threaded end of said tubular guide for supporting said center punch in position, and a U-shaped lock spring means in said tubular guide and said front enclosure of said frame for engaging said annular groove and thereby holding said center punch in position.
